SNOWPLOW

Daniel Hoare, Kremmling, Colo., assignor of one-half to Marcus F. Church, Granby, Colo.

Application February 27, 1939, Serial No. 258,666

2 Claims. (Cl. 37—44)

This invention relates to improvements in snowplows.

One object of the invention is to provide a snowplow that is readily attachable to a motor vehicle or the like, by novel means.

Another object is to provide a snowplow of this character that is supported as a cantilever on a motor vehicle.

A further object is to provide a snowplow that is readily adaptable to various types of motor vehicles.

A still further object is to provide means for attaching such a snowplow to a motor vehicle that will permit a limited vertical movement of the plow with reference to the vehicle, to facilitate the plow passing over immovable obstructions in its path.

Still another object is to provide a snowplow that can be used to discharge snow at both sides and that also may be adapted to discharge at one side only.

A further object is to provide in a plow of this character, wings that are particularly well adapted to discharge snow or the like in an unusually efficient manner.

Other objects and advantages reside in details of design and construction which will be more fully disclosed in the following description and in the drawings wherein like parts have been similarly designated and in which:

Figure 1 is a plan view of a snowplow that is constructed according to the present inventive concept;

Figure 2 is a side elevation of the plow shown in Figure 1;

Figure 3 is a fragmentary, sectional view taken along the line 3—3 of Figure 1;

Figure 4 is a fragmentary, sectional view taken along the line 4—4 of Figure 1;

Figure 5 is a fragmentary view of a modified form of the invention;

Figure 6 is a fragmentary plan view illustrating the specific details of a preferred form of the invention;

Figure 7 is a fragmentary view illustrating another modification of the invention;

Figure 8 is a fragmentary view taken along the line 8—8 of Figure 1; and

Figure 9 is a fragmentary view taken along the line 9—9 of Figure 1.

The accompanying drawings illustrate a typical reduction to practice of the present inventive concept and while this device has hereinabove been referred to as a snowplow, obviously it can be used for moving earth or other movable matter.

In the drawings, reference character 15 denotes a central beam which is preferably made telescoping to facilitate attachment and removal, as shown at 16. A pin or pins 17, Figure 3, may be inserted in holes 18, Figure 1, in the telescoping beam 15—16 to hold the same against separation during backward movement.

The beam 15 is adapted to be supported as a cantilever by means of an apertured vertical support 19 having an eye 20, Figure 4, through which the beam 15 passes and is held in any suitable manner, such as by welding, riveting, etc. The beam 15 is illustrated as being made of tubular iron or steel construction, but obviously, it could be made of other material and/or cross sectional shape, as preferred.

The vertical support 19 is adapted to pass through an apertured bracket 21 on a bar 22 that is to be affixed to the regular bumper 23 of any motor vehicle 24. The bar 22 may conveniently be attached to the bumper 23 by means of clamps or clevises 25.

The rearward end of the beam 15 is adapted to be attached to the front axle of the motor vehicle, as indicated in dotted lines at 26. A convenient means of attaching the rearward end of said beam to said axle is by means of a clevis 27. Pins 21a may be inserted through selected apertures in the support 19 above and below the bracket 21 to hold the beam 15 in a desired position of elevation above the ground.

Clevis 27 effects a loose connection of the rear end of beam 15 to the front axle of the vehicle. A clevis is inherently a means for loosely connecting two members. Furthermore, referring particularly to Figure 9, the square aperture adjacent the lower portion of clevis 27 and below axle 26 provides a loosely fitting entrance for the extreme rear end of beam 15 which is reduced in size as clearly shown in Figure 2 to fit freely and loosely into said aperture in the clevis.

Pins 21a are shown in Figures 2, 3 and 4 as in close proximity to bracket 21, nevertheless the lower pin may be positioned slightly below the bracket to permit limited relative movement of the vertical support 19 which supports the beam 15, with reference to the bracket 21 and the car bumper. Such movement permits the plow assembly as a whole to rise slightly over immovable objects in its path, such as, for instance, outcropping stones in a roadway. Furthermore, the inherent resiliency of the sprung portion of the motor vehicle, which includes the bumper, permits a certain amount of upward movement of

the snowplow since said plow is supported on the bumper. Obviously, the bumper of a typical motor truck or other automobile or similar vehicle may move up and down with reference to the roadway over which the vehicle is traveling due to the spring mounting of the frame of the vehicle. An important advantage is effected by supporting the present plow on the bumper of a typical motor vehicle.

10 In the preferred form of the present invention, the beam 15-16 carries a pair of angularly related blades or wings 28 that are preferably joined at the outer end of the beam 15-16, at a 90° angle with reference to each other. A piece 15 of standard angle iron, shown at 29, may be used to overlie the vertex of the angle of the wings 28. A runner-like member 30 may be provided adjacent the vertex of the plow to facilitate its riding over an immovable obstacle in its path.

20 A cross member 31 may be supported on the beam 15-16 to connect at its extremities with the side wings of the plow, 28, to maintain their angular relationship.

Toward the rearward ends of the respective wings 28 are apertured supports 32, shown best in Figure 8. Supports 32 are attached at selected elevations to angle brackets 33 that are conveniently attached adjacent the outer extremities of the bar 22. The supports are attached to 25 the wings 28 of the plow by means of bolts or the like, shown at 32. Eyes 35 in the respective supports 32 fit around the respective bolts 34 to permit limited vertical movement of the wings 28 with reference to the operating vehicle, to facilitate the passage of said wings over immovable obstacles. The rearward extremities of the wings 28 are preferably cut at an angle of about 45, as best shown at 36, Figure 8. Metal runners indicated at 37, may advantageously be used along 30 the lower edges of the wings 28.

40 Obviously, the form of the improved snowplow illustrated in Figures 1 and 2 would be effective for discharging snow or other moved material, at both sides as the plow is driven by the motor vehicle.

In the modified form shown in Figure 5, a socket 38 is adapted to be placed on the forward end of the beam 15. The socket 38 has an angle plate 39 to which a single blade or wing 28a may 45 be attached, thereby providing a plow, earth mover, or the like, that is adapted to discharge at one side only. It will be understood that in the form of the invention illustrated in Figure 5, the means for supporting the beam 15 would be 50 similar to the supporting means hereinabove set forth. Braces not shown, could be readily attached to the blade or wing 28a adjacent the extremities thereof and connecting with the bar 22 on the bumper 23, to provide additional support.

60 In Figure 6, a socket 38a is provided with an angular flange 40 to which the wings 28 may be conveniently attached to form the above described V-shaped plow arrangement.

65 In Figure 7, a socket 38b is provided with a flange 41 to which straight blade 42 may conveniently be attached for moving snow, earth or the like. Thus by providing a plurality of sockets 38, 38a and 38b, this improved material 70 mover can be adapted to various types of work according to varying operating conditions.

The use and operation of the improved snowplow appears obvious. The bar 22 may be af-

fixed to the car bumper 23 and it may remain there semi-permanently. The beam 15 carrying the wings or blades of the plow may readily be attached to the motor vehicle as hereinabove set forth, when snow, earth or the like is to be moved. 5 Since the plow is supported in front of the motor vehicle as a cantilever, no portion thereof drags upon the surface over which the plow is moved. There normally is a definite space between the lower edge of the plow and the surface of the 10 ground, as clearly illustrated in Figure 2. If and when an obstacle such as a rock, is encountered, the plow will normally slide thereover, being facilitated in such a function by the runner-like point 30 and the movable supporting 15 mechanism illustrated in Figure 8. This improved plow may, therefore, be operated with a minimum of power and at a relatively high speed, due to the fact that there is no frictional drag 20 of the plow on the surface of the earth. 20

The angular outward extremities of the plow blades or wings 28 as shown at 36, Figure 8, have been found to greatly facilitate the flow of material off of the plow. These angular ends provide a discharge for moved material and they reduce the amount of power required to move the plow against the resistance of such material. Furthermore, the banks formed by the material being moved at either extremity of the plow blades, are graded outwardly from the plow so 30 that there is definitely less tendency for the material to fall or slide back into the cleared area. 25

While this specification discloses preferred means for reducing the present invention to practice and a preferred embodiment of the invention, changes may occur to those skilled in the art and may be made within the scope of the appended claims, without departing from this inventive concept. 35

What I claim and desire to secure by Letters 40 Patent is:

1. In snowplow construction, mold boards arranged in V-shaped formation, an upturned runner at the vertex of such V-shaped formation, a beam element connected with said V-shaped formation, means for loosely attaching the rear of the beam element to the front axle of a motor vehicle, a bracket attached to the front bumper of the motor vehicle, means for loosely supporting the beam element on said bracket for limited up and down movement relative thereto, the beam element being supported as a cantilever projecting forwardly of said bumper, and means for supporting said mold boards from the bumper of the vehicle for limited relative up and down movement, the entire snowplow assembly being thus supported as a cantilever projecting forwardly of the vehicle and spaced above the normal surface of the roadbed over which the vehicle travels. 50 55

2. In snowplow construction, means for supporting the plow on a vehicle inclusive of an axle and a bumper, comprising a beam member, means for attaching the beam to the axle of the vehicle, an apertured bracket on the bumper, an apertured, upright support for the beam intermediate its ends and positioned through said bracket, and a pin through said upright support and bearing on said bracket for holding the beam on said vehicle as a cantilever, and permitting 65 70 limited upward movement of the snowplow.

DANIEL HOARE.
